UNITED STATES PATENT OFFICE.

ROBERT A. ROBERTSON AND JOHN GEORGE HUDSON, OF GLASGOW,
SCOTLAND.

CANE-MILL.

SPECIFICATION forming part of Letters Patent No. 391,337, dated October 16, 1888.

Application filed June 7, 1888. Serial No. 276,335. (No. model.) Patented in England January 14, 1887, No. 602.

To all whom it may concern:

Be it known that we, ROBERT ANDREW ROBERTSON and JOHN GEORGE HUDSON, both of the firm of Mirlees, Watson and Company, 5 Scotland Street Iron Works, Glasgow, in the counties of Lanark and Renfrew, North Britain, engineers, have invented Improvements in Cane-Mills, (for which we have obtained Letters Patent in Great Britain on the 14th of 10 January, 1887, numbered 602,) of which the following is a specification.

This invention, which relates to improvements in the construction of mills for expressing juice from sugar-cane or analogous saccharine plants, has reference to that class of mills in which two or more pairs of rollers are arranged in such a position that a line drawn through the axis of each pair of rollers 15 is parallel to a similar line drawn through the axes of the other pair or pairs of rollers.

The present improvements relate especially to the gearing by which the rolls of mills so arranged are connected and driven, and for this purpose a shaft is carried either above or 25 below the framing and provided with a pinion of equal diameter at each side of the mill. Each pinion drives a train of gearing so arranged as to connect the top roller of one pair with the bottom roller of the next pair, and 30 so on, the top and bottom rollers, respectively, of each pair being connected with the opposite trains of gearing.

Mills constructed according to these improvements may be placed horizontally, but 35 by preference they are arranged inclined, in order that the passage of the crushed cane from one pair of rollers to the succeeding pair may be aided by gravity.

Figure 1 of the annexed drawings is an end 40 view of a four-roller sugar-cane mill constructed in accordance with these present improvements. Fig. 2 is a side view of the same.

In the mill illustrated by these drawings the pairs of rollers A and B and C and D are carried in an inclined framing, E, and two such 45 pairs of rollers only are shown as being sufficient for the purpose of illustrating this invention; but it is to be understood that more than two pairs of such rollers may be used. 50 The shaft F below the framing is the driving-shaft, and carries at its ends the pinions G and H, respectively. The pinion G gears into the toothed wheel I on the lower roller, B, of one pair of rollers, which again gears into the

toothed wheel J of the upper roller, C, of the other pair of rollers, while the other pinion, H, gears into the lower toothed wheel, K, on the axis of the lower roller, D, which again gears into the toothed wheel L of the upper roller, A.

The cane may be fed into the machine in the usual manner by a chain carrier, and as the trash leaves the second pair of rollers, C and D, it may be carried away by another chain carrier, as shown by the dotted lines in 65 Fig. 1.

It is to be understood that when more than two pairs of rollers are used the toothed wheel on the lower roller of one pair of rolls gears with the toothed wheel on the upper roller of 70 the next pair of rolls, and so on continuously for any number of pairs of rolls.

By means of the improvements constituting this invention the trash-turner or its equivalent, commonly employed and necessary in the 75 ordinary three-roller sugar-cane mill, is dispensed with, and the small pinions commonly employed in such mills replaced by the larger toothed wheels employed in connection with these improvements.

We claim—

The combination, in a cane-mill, of a pair of rollers, A and B, a lower pair of rollers, C and D, driving-shaft F, arranged between and below said pairs of rollers, pinions G and H 85 on the ends of the driving-shaft, toothed wheel I on one end of the lower roller of the pair of rollers A and B, toothed wheel J on one end of the upper roller of the pair of rollers C and D, said toothed wheels I and J intermeshing, and wheel I intermeshing with pinion G, toothed wheel K on one end of the lower roller of the pair of rollers C and D, and toothed wheel L on one end of the upper roller of the pair of rollers A and B, said wheels K 90 and L intermeshing, and wheel K intermeshing with pinion H, substantially as shown and described.

In testimony whereof we have signed our names to this specification in the presence of 100 two subscribing witnesses.

R. A. ROBERTSON.
JOHN GEORGE HUDSON.
